G. E. LA MARCHE

ORGAN VALVE ACTION UNIT

Filed April 7, 1927

12 16 50 Inventor:
By J. Clark Stages, attq.

UNITED STATES PATENT OFFICE.

GEORGE E. LA MARCHE, OF CHICAGO, ILLINOIS.

ORGAN-VALVE-ACTION UNIT.

Application filed April 7, 1927. Serial No. 181,796.

This invention relates to organ valve-action, and more particularly concerns the construction and arrangement of individually removable valve-action units.

An important object of the invention is to provide a construction which will permit a series of such valve-action units to be compactly arranged and secured in conveniently accessible position; which will provide for the simple and quick removal, inspection, and replacement or exchange of the individual units; and which will be equally well adapted for use in connection with differently designed and differently scaled organ valve-chests.

Another important object is to provide a simple and economical construction which may be manufactured by, or furnished to, organ builders in quantities and may be kept in stock, ready for immediate installation or exchange; and which will be highly efficient in operation.

Further objects and advantages of the invention will appear in the detailed description to follow.

In the drawings—

Figure 1 is a vertical, fore-and-aft sectional view of part of a pipe-organ valve-chest, illustrating one method of employing the present invention in connection therewith and showing the several valves in closed position;

Fig. 2 is a vertical, fore-and-aft sectional view of a detached valve-action unit, upon an enlarged scale, taken upon the line 2—2 of Fig. 3, showing the valves thereof in open position;

Fig. 3 is a perspective view of a detached valve-action unit, illustrating the method of sealing the sides thereof without adding materially to the width of the structure; and

Fig. 4 is a perspective view of several of the individually removable valve-action units mounted in operative position, illustrating the compact and conveniently accessible arrangement thereof.

As is well known in modern organ building, the individually removable and interchangeable unit features present many highly desirable advantages, not necessary to recite here, the principal and perhaps only objections thereto which have heretofore obtained being those of increased cost of manufacture and the additional space usually required. These objectionable features are entirely absent in the construction here pre-

sented. Mill-room cuttings, which would be otherwise wasted, may here be employed to advantage, and the construction here provided permits the several units to be mounted in unusually close and compact order.

The method here disclosed of separately arranging and securing the individual units in position avoids the danger of inter-communicating leaks or "runs", and facilitates the location and remedying of faults pertaining to the individual valve-actions of the different valve-chests. Various other advantages will be recognized by those conversant with the organ building art.

Referring to Figure 1, one end-portion of an organ valve-chest channel-board 1 is shown extending over two stop-chambers 2—2 and supporting the organ pipes 3—3 pertaining to said stop-chambers, respectively. The stop-chambers extend transversely to the channel-board 1 and the several pipes representing the notes of each stop extend in rows over their respective stop-chambers and communicate therewith through corresponding ports, or "pipe-holes", 4—4 in the usual or any desired manner. For convenience in illustration, but two stop-chambers and one pipe of each of the corresponding stops have been shown. A series of note-channels, such as the channel 5, are arranged parallel to each other, one for each note, in the channel-board 1 to extend over the several stop-chambers, each note-channel passing at the side of the ports 4—4 of the pipes representing its respective note in the different stops. Arranged within each stop-chamber 2 is a horizontally extending valve-shelf 6, and arranged along this valve-shelf 6, and

95 of pipe-valves, such as 7, there being one valve 7 for each pipe 3 or note of each stop. The particular construction of these pipe-valves 7 form the subject-matter of a co-pending application, Serial No. 159,120, filed January 5th, 1927, and will here be but briefly described. Each valve 7 comprises a stool-shaped body 8 having hollow communicating cup and stem portions, the top of the cup-portion being covered by a flexible 105 diaphragm 9 which is secured about the rim of said cup-portion and carries upon its outer surface a centrally secured valve-disc 10, and the stem-portion being supported and secured in position upon the valve-shelf 110 6, each valve being arranged beneath and in axial alignment with the respective port,

4 which it controls. Valve-shelf 6 is provided with individual ducts 11 which connect the hollow interior of each valve 7 with its corresponding note-channel 5. The different stops of pipes 3 are brought into service by supplying the respective stop-chambers 2 with air-pressure, or "wind", and the individual operation of the valves 7 is controlled by the alternate release and admission of air-pressure in the corresponding note-channels 5. The surface area of each diaphragm 9 is materially greater than that of the port 4 which it controls, so that, when air-pressure is released, through the respective note-channel 5 and duct 11, from the interior of the hollow body 8, the presence of air-pressure within a selected stop-chamber 2 will force the diaphragm downwardly, open the respective port and sound 20 the corresponding pipe 3. Upon the re-admission of air-pressure to the note-channel 5, diaphragm 9 will be placed in equilibrium and the draft of air passing through port 4 to pipe 3 will effect the closing of 25 the valve, all in the manner well understood in this art.

It may be well to mention, at this point, that a quicker and more positive operation of the pipe-valves is sometimes obtained by 30 serving the note-channels 5 with a higher degree of air-pressure than that employed in the stop-chambers 2 for blowing of the pipes. Similarly, as fully described in the aforesaid application, Serial No. 159,120, 35 the valves 7 may be provided with an expansive coil spring (not here shown), located within the stool-shaped body 8 and acting outwardly upon the inner surface of the diaphragm 9. Either of such provisions will 40 permit the valves to be opened farther from their ports, the closing of the valves not being wholly dependent upon the draft of air through such ports.

This invention more particularly concerns 45 the construction and arrangement of the valve-action for controlling the admission and release of air-pressure to and from the note-channels 5, such valve-action being in turn controlled in operation from the usual manual keys or, if the instrument be automatically controlled, from the well-known music-sheet-and-tracker mechanism. Neither the manual keys nor the tracker mechanism are here shown, since they do not 50 form a part of this invention and may be of conventional or any desired construction.

In the preferred arrangement here illustrated, the several valve-action units 12 are suspended beneath the forward part of the valve-chest and are individually secured directly upon the channel-board 1, but it is to be understood that they may be differently positioned without altering their operation or efficiency. With this present arrangement, each note-channel 5 opens outwardly

upon the under surface of the channel-board 1, an air-pressure chamber 13 is arranged to extend transversely across the upper surface of the channel-board 1, and a series of channels 14, one for each note, extend vertically 70 through the channel-board forward of the downwardly presented ends of the respective note-channels 5, communicating with the air-pressure chamber 13 and providing a separate air-pressure supply-channel for 75 each valve-action unit 12. Suitable packing material 15, such as leather or sheet cork, is preferably cemented upon the upper surface of each unit 12, so that, when the unit is secured in position upon the channel-board 80 1, the air-passages therein will be held in air-tight communication with the corresponding note-channels 5 and supply-channels 14.

The valve-action units 12 are all similarly 85 constructed and are preferably interchangeable; consequently, a description of one will serve for all. The frame-work of each unit 12 comprises a base-member 16 and a pair of ported strips 17 and 18 (Figs. 2 and 3), 90 spaced from each other and secured together at their end-parts by spacing blocks 19, 20, 21 and 22, to form a flat rectangular structure. Preferably, these parts are provided with their several channels and ports before 95 being assembled. When the parts of the unit are assembled and secured together, the sides of the structure are properly trimmed and faced, the various interior elements are placed and adjusted in position, and the flat 100 side faces of the unit are sealed by sheets of thin, flexible, air-tight material 23, such as paper or rubber-cloth, so that the spaces formed between the parts 16, 17 and 18, become closed chambers 24 and 25. 105

Base-member 16 is formed with fore-and-aft projecting slotted lugs 26 and 27 which extend beyond each end of the body of the unit and are each transfixied by a screw 28 for removably securing the unit in position 110 upon the valve-chest. An inner chamber 29 is formed in base-member 16, as here shown, by three communicating, divergently extending, elliptical borings or channels 30, 31 and 32 (Fig. 2). Viewing the unit as 115 shown in the drawings, channel 30 extends vertically to the upper horizontal surface of base-member 16 and constitutes an air-pressure supply-channel, arranged to communicate with its respective supply-channel 14 when the unit is in its proper position upon the valve-chest. Channel 31 extends horizontally to the forward vertical surface of base-member 16 and provides a housing for an electro-magnet unit 33, to be 120 later described, while channel 32 extends vertically to the lower horizontal surface of base-member 16 and constitutes an air-pressure supply-channel for middle diaphragm-chamber 24. A diaphragm-cell 34 is pro- 125

vided in the lower surface of base-member 16 and is preferably formed therein by a wide groove extending transversely thereacross. A vertically extending channel 35 is formed in the unit by a boring extending from the upper horizontal surface of base-member 16 rearwardly of channel 30, inner chamber 29 and middle chamber 24, and through spacing block 20 and strip 17, to meet and communicate with outer valve-chamber 25. Channel 35 is arranged to communicate with the downwardly turned end of its respective note-channel 5 when the unit is properly positioned upon the valve-chest. A duct 36 is bored in base-member 16, extending from the forward vertical surface thereof, just below the forward open end of channel 31, to diaphragm-cell 34. With respect to this part of the construction 20 of the unit 12, it will be noted that the several elements thus far described may be conveniently milled separately and then assembled and glued, or otherwise secured, together to form a single unit.

25 A flexible diaphragm 37, preferably of thin leather, is cemented, or otherwise secured, upon base-member 16 to completely cover and enclose diaphragm-cell 34, the side edge-parts of said diaphragm being 30 brought around and secured upon the sides of the base-member, as shown at 38 (Fig. 3). A comparatively thin, narrow strip 39 of suitable material, such as leather or wood, is secured upon diaphragm 37, and the inner 35 end-parts of a pair of valve-stems 40 and 41 are threaded into strip 39, so that vibration of the diaphragm will effect the reciprocation of said valve-stems. Valve-stems 40 and 41 pass through inner valve-ports 42 and 43 in strip 17, and through outer valve-ports 44 and 45 in strip 18, respectively, and their outer end-parts are guided by being passed through a guide-strip 46 which is secured upon the outer surface of strip 18.

45 A valve 47 is carried upon valve-stem 40 between valve-ports 42 and 44, and a corresponding valve 48 is carried upon valve-stem 41 between valve-ports 43 and 45. Valve-ports 42 and 43 connect outer valve-chamber 50 25 with middle diaphragm-chamber 24, and valve-ports 44 and 45 connect said outer valve-chamber with the atmosphere. Vibration of diaphragm 37 may thus effect the shifting of both valves 47 and 48 and there-55 by control the admission and release of air-pressure to and from outer valve-chamber 25. This arrangement of valve-ports and valves for control by a single, narrow, elongated diaphragm provides for the control of a considerable volume of air and, at the same time, permits the construction of the complete unit to be made unusually narrow.

When the parts have been secured and adjusted to provide for their proper operation, 60 as described, the opposite side faces of the

unit are covered and sealed by cementing, or otherwise securing, the sheets of material 23 thereupon. It will be noted that this method of sealing the sides of the unit provides an air-tight and substantial closure 70 which may be removed and replaced with comparative ease and without damaging the frame-work of the unit, providing for convenient access to the interior of the structure and, at the same time, constituting an 75 important factor in producing a unit construction of minimum thickness or width.

The construction of the electro-magnet unit 33 herein shown does not form a part of this invention and will be but briefly described. A metal base-plate 49 is removably secured in position upon the forward vertical surface of the unit 12 by means of screws, one of which is shown at 50, covering the open ends of channel 31 and duct 36 80 and supporting the electro-magnet 51 in channel 31. Base-plate 49 is perforated with a port 52 communicating with channel 31, and with a port 53 communicating with duct 36, and is provided with a pair of retaining hook-clips 54—54 which are swiveled or threaded to turn therein. A channeled cap-plate 55 is removably held by hook-clips 54—54 upon the outer face of base-plate 49, the channel therein extending over and connecting ports 52 and 53, housing and guiding an armature-valve 56, and carrying a hollow screw 57 which is threaded through the forward wall of said cap-plate and constitutes an adjustable valve-seat and atmosphere-port for said armature-valve. Armature-valve 56 is positioned to play between and control port 52 and the port formed by hollow screw 57. Packing material (not shown) may be employed between base-plate 49 and cap-plate 55, and between said base-plate and the forward surface of the unit 12, to insure air-tightness.

The operation of the entire device will now be described. Assuming that the electro-magnets 51 for the several units 12 are individually connected in circuit with corresponding key-controlled or tracker-controlled (or both) switches, and that air-pressure exists in both stop-chambers 2—2 110 and in chamber 13, the inoperative position of the several movable parts will be as shown in Figure 1. Considering the operation of a single unit 12 as illustrative of all, the air-pressure in chamber 13 will be communicated, through channel 14 and channels 30 and 32, to chambers 29 and 24, and will be effective upon both sides of diaphragm 37, since the armature-valve 56 of electro-magnet unit 33 will be blown against the valve-seat formed by the inner end of hollow screw 57 to close this outlet-port, and diaphragm-cell 34 will be provided with air-pressure through chamber 29, ports 52 and 53 (connected by the channeled cap-plate 55), 125 130

and through duct 36. While diaphragm 37 thus remains in equilibrium, valves 47 and 48 will be held blown against their respective outer valve-ports 44 and 45 and away from their inner valve-ports 42 and 43, to serve air-pressure to chamber 25 and thence to note-channel 5, through channel 35. The effect of this admission of air-pressure to note-channel 5 upon the several pipe-valves 7 connected therewith has been described. They will be closed and the respective notes or pipes 3 will be silent.

If, now, the electro-magnet 51 be energized through the closing of the switch with which it is in circuit (i. e., by the operation of the respective manual key or the tracker mechanism heretofore mentioned), armature-valve 56 will be attracted thereby away from the valve-seat formed by the inner end of hollow screw 57 to open this outlet or atmosphere port, and will close port 52 in base-plate 49, cutting off the supply of air-pressure to diaphragm-cell 34 and connecting it with the atmosphere. Diaphragm 37 being of substantially greater area than the combined areas of ports 42 and 43, and of ports 44 and 45, the air-pressure in chamber 24 will effect the operative positioning of the parts as shown in Fig. 2, raising valves 47 and 48 to open valve-ports 44 and 45 and close valve-ports 42 and 43, thus cutting off the admission of air-pressure to note-channel 5 and venting it to the atmosphere. The effect of this release of air-pressure from note-channel 5 upon the several pipe-valves 7 connected therewith has also been described. They will be opened and the respective notes or pipes 3 will be sounded, according to the selective admission of air-pressure to the stop-chambers 2, also hereinbefore described.

I claim—

1. A valve-action unit of the character specified, comprising a flat rectangular frame formed of longitudinally parallel members and spacing members secured to and between the end-parts of said parallel members to surround and define an inner space, and a thin sheet of air-tight flexible material secured upon each opposite flat face of said frame to completely enclose said inner space.

2. A valve-action unit of the character specified, comprising a flat rectangular structure formed of a plurality of longitudinally parallel members and spacing members secured to and between the end-parts of each of said parallel members to surround and define a plurality of intervening spaces, and a thin sheet of air-tight flexible material secured upon each opposite flat face of said structure to completely enclose said intervening spaces.

3. A valve-action unit of the character specified, comprising a flat rectangular

frame formed of longitudinally parallel members and spacing members secured to and between the end-parts of said parallel members to surround and define an inner space, a chamber within one of said parallel members, a passage extending between said chamber and said inner space and a passage extending from said chamber and opening out upon an outer face of said frame, and a thin sheet of air-tight flexible material secured upon each opposite flat face of said frame to completely enclose said inner space.

4. A valve-action unit of the character specified, comprising a flat rectangular structure formed of a plurality of longitudinally parallel members and spacing members secured to and between the end-parts of each of said parallel members to surround and define a plurality of intervening spaces, passages extending through certain of said members from one outer face of said structure to each of said intervening spaces, and a thin sheet of air-tight flexible material secured upon each opposite flat face of said structure to completely enclose said intervening spaces.

5. A valve-action unit of the character specified, comprising a base-member and a plurality of members secured thereto and combining therewith to form a first chamber, an inner chamber and a diaphragm-cell formed in said base-member, a passage connecting said chambers, a diaphragm covering said diaphragm-cell and forming a flexible wall between said diaphragm-cell and said first chamber, a duct extending from said diaphragm-cell to an outer face of said base-member, a channel extending from said inner chamber and opening out upon said outer face of said base-member adjacent to the outer opening of said duct, and an electro-magnet housed within said channel and controlling the communication of said channel with said duct.

6. A valve-action unit of the character specified, comprising a base-member and a plurality of members secured thereto and combining therewith to form a first chamber, an inner chamber and a diaphragm-cell formed in said base-member, a passage connecting said chambers, a diaphragm covering said diaphragm-cell and forming a flexible wall between said diaphragm-cell and said first chamber, a duct extending from said diaphragm-cell to an outer face of said base-member, a channel extending from said inner chamber and opening out upon said outer face of said base-member adjacent to the outer opening of said duct, and an electro-magnet unit comprising a valve-chamber, an electro-magnet secured to said electro-magnet unit, and an armature-valve within said valve-chamber; said valve-chamber being secured upon said outer face of

said base-member to cover and connect the outer openings of said channel and said duct; said electro-magnet being housed within said channel; and said armature-
5 valve controlling the communication of said channel with said duct.

7. A valve-action unit of the character specified, comprising a base-member and a plurality of members secured thereto and combining therewith to form a middle chamber and an outer chamber, an inner chamber and a diaphragm-cell formed in said base-member, a passage connecting said middle and inner chambers, a valve-port
10 connecting said middle and outer chambers, a valve-port connecting said outer chamber with the atmosphere, a diaphragm covering said diaphragm-cell and forming a flexible wall between said diaphragm-cell and said middle chamber, a valve within said outer chamber controlling each of said valve-ports, a connection between said diaphragm and said valve, a duct extending from said diaphragm-cell and opening out upon an
15 outer surface of said base-member, a channel extending from said inner chamber and opening out upon said outer surface of said base-member adjacent to the outer opening of said duct, and valve-means secured upon
20 said outer surface of said base-member operating to control the communication of said channel with said duct.

8. A valve-action unit of the character specified, comprising a base-member and a plurality of members secured thereto and combining therewith to form a middle chamber and an outer chamber, an inner chamber and a diaphragm-cell formed in said base-member, a passage connecting said middle and inner chambers, a plurality of valve-ports connecting said middle and outer chambers, a plurality of valve-ports connecting said outer chamber with the atmosphere, a diaphragm covering said diaphragm-cell and forming a flexible wall between said diaphragm-cell and said middle chamber, a plurality of valves within said outer chamber each controlling two of said valve-ports, a connection between said diaphragm and each of said valves, a duct extending from said diaphragm-cell and opening out upon an outer surface of said base-member, a channel extending from said inner chamber and opening out upon said outer surface of said base-member adjacent to the outer opening of said duct, and valve-means secured upon said outer surface of said base-member operating to control the communication of said channel with said duct.
55
60

9. A valve-action unit of the character specified, comprising a base-member and a plurality of members secured thereto and combining therewith to form a middle cham-

ber and an outer chamber, an inner chamber 65 and a diaphragm-cell formed in said base-member, a passage connecting said middle and inner chambers, a first channel extending from said outer chamber and opening out upon a first outer surface of said base-member, a second channel extending from said inner chamber and also opening out upon said first outer surface of said base-member, a third channel extending from said inner chamber and opening out upon 70 a second outer surface of said base-member, a duct extending from said diaphragm-cell and also opening out upon said second outer surface of said base-member adjacent to the outer opening of said third channel, a valve-port connecting said middle and outer chambers, a valve-port connecting said outer chamber with the atmosphere, a diaphragm covering said diaphragm-cell and forming a flexible wall between said diaphragm-cell and said middle chamber, a valve within 75 said outer chamber controlling each of said valve-ports, a connection between said diaphragm and said valve, and valve-means secured upon said second outer surface of 80 said base-member operating to control the communication of said third channel with said duct.

10. A valve-action unit of the character specified, comprising a flat rectangular 95 frame formed of a longitudinally extending base-member and a plurality of members secured thereto and combining therewith to form middle and outer open-sided chambers, an inner chamber and a diaphragm-cell 100 formed in said base-member, a passage connecting said middle and inner chambers, a valve-port connecting said middle and outer chambers, a valve-port connecting said outer chamber with the atmosphere, a diaphragm 105 covering said diaphragm-cell and forming a flexible wall between said diaphragm-cell and said middle chamber, a valve within said outer chamber controlling each of said valve-ports, a connection between said diaphragm and said valve, a duct extending 110 from said diaphragm-cell and opening out upon an outer surface of said base-member, a channel extending from said inner chamber and opening out upon said outer surface of said base-member adjacent to the outer opening of said duct, valve-means secured upon said outer surface of said base-member operating to control the communication of 115 said channel with said duct, and a thin sheet of air-tight flexible material secured upon each opposite flat face of said frame to close and seal the open sides of said middle and outer chambers.
120

In witness whereof, I have hereunto subscribed my name this fourth day of April, A. D. 1927.

GEORGE E. LA MARCHE.
